[57] CLAIM

The ornamental design for a set of speakers, as shown and described.

DESCRIPTION

FIG. 1 is a front elevational view of a first speaker of a set of speakers, shown separately for clarity of illustration, showing my new design;

FIG. 2 is a top plan view thereof;

FIG. 3 is a right side elevational view thereof;

FIG. 4 is a left side elevational view thereof;

FIG. 5 is a rear elevational view thereof;

FIG. 6 is a bottom plan view thereof; and,

FIG. 7 is a front elevational view of a second speaker of a set of speakers shown separately for clarity of illustration; the undisclosed right side elevational view, left side elevational view and the bottom plan view being mirror images of the first speaker; and the rear elevational view and top plan view being the same, as the first speaker.
